DESIGN.

—o—
A. COCHRAN,
CARPET.

No. 17,434.

Patented July 12, 1887.

UNITED STATES PATENT OFFICE.

ANDREW COCHRAN, OF PHILADELPHIA, PENNSYLVANIA.

DESIGN FOR A CARPET.

SPECIFICATION forming part of Design No. 17,434, dated July 12, 1887.

Application filed June 15, 1887. Serial No. 241,429. Term of patent 3½ years.

To all whom it may concern:

Be it known that I, ANDREW COCHRAN, of the city of Philadelphia, county of Philadelphia, State of Pennsylvania, have invented and produced a new and original Design for Carpets, of which the following is a specification.

The nature of my design is fully represented in the accompanying photographic illustration, to which reference is made.

I claim—

The design for carpets, as herein shown and described.

Witnesses: ANDREW COCHRAN,
WILLIAM B. KEEFER,
GEO. W. LAMON.
